UNITED STATES PATENT OFFICE.

FRANK B. DE MUND, OF EAST STROUDSBURG, PENNSYLVANIA.

AIR-COUPLING.

1,370,790.

Specification of Letters Patent.

Patented Mar. 8, 1921.

Application filed April 29, 1920. Serial No. 377,599.

To all whom it may concern:

Be it known that I, FRANK B. DE MUND, a citizen of the United States, residing at East Stroudsburg, in the county of Monroe and State of Pennsylvania, have invented a new and useful Air-Coupling, of which the following is a specification.

It is the object of this invention to provide novel means whereby the air hose on railroad cars may be coupled and uncoupled without rendering it necessary for a trainman to enter between the cars.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in top plan, a device constructed in accordance with the invention; Fig. 2 is a vertical longitudinal section of the structure shown in Fig. 1, parts being broken away; Fig. 3 is a cross section taken approximately on the line 3—3 of Fig. 2; Fig. 4 is a cross section on the line 4—4 of Fig. 1; and Fig. 5 is an end view showing one of the coupling elements.

The device includes a pair of supports 1 and 2 preferably of rectangular cross section and having projecting parts 3 whereby the supports may be connected to rolling stock of any kind. The supports 1 and 2 are provided with depending flanges 4 connected by a front bolt 5 and a rear bolt 6. A member 7 is mounted for longitudinal reciprocation in the support 2, a similar member 8 being mounted for reciprocation in the support 1. The member 7 has a bore 9, the bore of the member 8 being denoted by the numeral 10. Tubes 11 are fixed in the outer ends of the members 7 and 8 and communicate with the bores 9 and 10, the tubes being slidably mounted in the outer end walls of the supports 1 and 2. With the outer end of each tube 11 is con-

nected a section of the air hose 12, the same being held in place by a clamp 14. Compression springs 15 are located in the supports 1 and 2 and abut at their outer ends against the end walls of the supports, the springs abutting at their inner ends against the members 7 and 8 and serving to advance the same. The members 7 and 8 are provided with depending loop-shaped projections 16 slidable between the flanges 4. When the members 7 and 8 are advanced by the springs 15, the projections 16 abut against the front bolts 5 which connect the flanges 4, and limit the forward movement of the said members.

The member 7 is provided with an enlargement 17 defining a shoulder 18. A nipple 19 is threaded in the outer end of the part 17 and is provided with a web 20. The numeral 21 denotes a ring having a flange 22 engaged between the web 20 and the end of the part 17, the ring 21 having a forward flange 23. The nipple 19 is provided with a plurality of spring fingers 24 extended outwardly and overlapped on the flange 23. Since the spring fingers 24 are overlapped on the flange 23, the flange acts as a guide or backing for the fingers, preventing their distortion. The web 20, co-operating with the part 17, serves to hold the ring 21 in place and the ring, that is, the flange 23 thereof, coacts with the fingers 24. There is a mutual interengagement between the parts alluded to, which results in a strong and compact structure.

The member 8 is provided with an enlargement 25 having a reduced end 26 into which is threaded a nipple 27 having an enlarged head 28, the nipple being provided with a flange 29, and a washer 30 being disposed between the flange 29 and the end 26 of the part 25. Clamp members 31 are mounted on the end 26 of the part 25 behind the washer 30 and in front of a shoulder 34 formed at the point where the end 26 merges into the part 25. The clamp members 31 are supplied with outstanding flanges 32 connected by combined fulcrum and clamp bolts 33.

Side levers 35 are fulcrumed on the bolts 33 and are located between the flanges 32, the levers having forks 36 adapted to engage behind the shoulder 18. Springs 37 are provided, the outer ends of the springs

engaging the side levers 35 in front of their fulcra 33, the intermediate portions of the springs being engaged around the bolts 33, and the inner ends of the springs being engaged with the flanges 32. The springs 37 tend to swing the outer ends of the levers 35 toward each other, so that the forks 36 will engage behind the shoulder 18. There is a boss 38 on the enlargement 25, the boss carrying a pivot element 42 whereon an intermediate lever 39 is fulcrumed, the lever 39 being connected by links 40 with the rear or inner ends of the side levers 35. The numeral 41 denotes an operating member pivoted to one end of the intermediate lever 39 and of sufficient length to extend outwardly to the side of the car wherewith the device is assembled, the construction being such that a trainman may operate the part 41 and consequently operate the levers 35, without entering between the cars or otherwise placing his life in jeopardy.

In practical operation, when the cars come together, the levers 35 are separated by engagement with the part 21 and, under the action of the springs 37, the forks 36 engage behind the shoulder 18. The enlarged head 28 of the nipple 27 enters with and is held by the spring fingers 24, and, thus, the trainline is established. Owing to the presence of the springs 15, the members 7 and 8 are advanced toward each other, so as to maintain connection established, as shown in Fig. 2 of the drawings, the springs 15, of course, minimizing the shock when the coupling elements are brought together. When it is desired to break the trainline, it is not necessary for the trainman to enter between the cars. The rod 41 may be operated from a point at the side of the cars, the lever 39 being tilted, and the links 40 tilting the levers 35, the forks 36 being brought out of engagement with the shoulder 18.

Having thus described the invention, what is claimed is:—

1. In a device of the class described, supports; members slidable in the supports and provided with coupling elements, one of said members having a shoulder; levers fulcrumed on the other of said members and adapted to coöperate with the shoulder; spring means coacting with the levers, to cause the levers to coöperate with the shoulder; another lever fulcrumed on said other member; links connecting said other lever with the first specified levers; and an operating member extended laterally from said other lever.

2. In a device of the class described, a support; a member slidable in the support; a nipple mounted at one end in said member and provided at its other end with spring fingers, the nipple having a web; a ring including a flange engaged between the web and the end of said member, and a flange engaged behind the fingers; and a second member having means for engaging the fingers.

3. In a device of the class described, supports; members slidable in the supports and provided with coupling elements, one of said members having a shoulder; levers fulcrumed on the other of said members and adapted to coöperate with the shoulder; spring means coacting with the levers, to cause the levers to coöperate with the shoulder; another lever fulcrumed on said other member; links connecting said other lever with the first specified levers; and means for operating said other lever.

In testimony that I claim the foregoing as my own, I have hereto affixed by signature in the presence of two witnesses.

FRANK B. DE MUND.

Witnesses:

LAWRENCE DALE,
B. W. LEE.
